UNITED STATES PATENT OFFICE.

JOSEPH DARLING AND BRADFORD H. GRISWOLD, OF FAIRVIEW, PA.

CURTAIN-FIXTURE.

SPECIFICATION forming part of Letters Patent No. 252,742, dated January 24, 1882.

Application filed September 7, 1881. (No model.)

To all whom it may concern:

Be it known that we, JOSEPH DARLING and BRADFORD H. GRISWOLD, citizens of the United States, residing at Fairview, (Baldwin P. O.), in the county of Butler, State of Pennsylvania, have invented a certain new and useful Improvement in Curtain-Fixtures, of which the following is a specification.

This invention has more particular reference 10 to that class of curtain-fixtures in which the entire fixture, including the roller, can be adjusted to different heights with relation to the window, but it is in part applicable to curtain-fixtures in which the bearings for the roller are 15 in fixed brackets.

The invention consists, first, in the devices 20 for rolling and unrolling the curtain and securing the same so that it can be raised or lowered and retained in any position by means of a single cord; second, in the combination, with 25 said devices, of means for raising and lowering the entire fixture independent of the rolling and unrolling of the curtain; third, in the details of construction and combination of parts, as hereinafter more fully set forth.

The accompanying drawings, which form a 30 part of this specification, represent a curtain-fixture constructed in accordance with the invention.

Similar letters of reference indicate like parts on all the figures.

Figure 1 is a perspective view of the improved curtain-fixture in place upon a window; Fig. 2, a similar view of the end of the 35 roller upon which are the devices for rolling and securing the curtain; Fig. 3, a sectional view of that part of the device shown in Fig. 2; Figs. 4, 5, and 6, detail views; and Fig. 7, a sectional view of the knob for securing the 40 main curtain-cord.

A is the window-frame, provided with rollers or buttons a a' at the upper corners, from which the curtain and its fixtures are suspended by the main cord B. One end of this 45 cord is attached to the movable guide-piece b, which also forms one of the bearings for the roller C, and the other end is attached to a swinging piece or disk, D. The cord B is passed from guide-piece B over button a , then 50 through the wire link or loop b' , then upward and over buttons a a' to the swinging disk D.

The whole curtain may be raised or lowered

by means of the single cord E, caught by a knot in link b' , and is secured by means of the double knob F.

The rolling or unrolling of the curtain is accomplished by means of a cord, c, which winds on a spool, c' , at one end of roller C. This cord c passes through a slot in arm d of swinging disk D. When the curtain is down the 60 cord is wound around the spool, and in raising it the cord is drawn down as customary.

On the end of roller C is secured a cap or disk, c^2 , which is prevented from twisting by means of lugs c^3 , which take into the end of 65 the roller. To this cap or disk is attached a second disk, G, provided with a collar, which forms the spool for cord c. Projections g on said collar fit into corresponding holes in disk or cap c^2 . On the opposite side of disk G is a 70 hub or boss, g' , and a collar, g^2 , forming a continuation of said hub or boss. Both disks c^2 and G have a central hole for the passage of a screw, g^3 , which screws into roller C, and the head of which, when secured in place, bears 75 against collar g^2 and clamps disks G and c^2 and roller C firmly together.

The swinging piece or disk D (see Fig. 5) has a central slot, d' , through which passes collar g^2 , and a second slot, d^2 , near its upper edge, 80 from which the hanging piece or hanger e is loosely hung by means of a pin, e^2 . This hanger (see Fig. 6) has a hole, e' , in its lower end to receive collar g^2 , and constitutes the bearing for roller C.

On the side of disk G adjacent to the swinging disk D are a number of lugs or projections, g^4 , arranged at equal distances from the center to form a ratchet-wheel. Swinging disk D has a single projection, d^3 , which, when collar g^2 is 90 in the back or lower part of slot d' , engages with one of projections g^4 on disk G and arrests the rotation of the roller.

The device for fastening cord E, by which the height of the fixture is regulated, consists 95 of two knobs, f f' , and a screw, f^2 , by which the knobs are secured to the window-frame. When the fixture is brought to the desired place the cord E is wound between knobs f f' and is secured by the pressure of their adjacent surfaces. For purposes of adjustment to different thicknesses of cord the head of screw f^2 is made square, as shown, and fits into a square hole in knob f , so that by turning the lat-

ter the distance between the knobs is increased or lessened, thus allowing the use of cord of greater or less thickness.

The operation of the device will be readily understood. The weight of the fixture keeps the collar g^2 normally in the lower or back part of slot d' , the projections d^3 being in contact with one of the projections g^4 . To raise the curtain or shade, cord c is pulled downward.

- 10 10. The pressure upon arm d of swinging disk D throws the lower portion of the latter back, thus throwing projection d^3 out of engagement with projections g^4 , and the roller C is permitted to revolve, thus rolling up the curtain.
- 15 15. When raised to the desired height cord c is suddenly released and projection d^3 enters into one of the spaces between projections g^4 and arrests the roller. To unroll the curtain or shade, swinging disk D is thrown back by pulling on cord c , as before, and the cord held with sufficient tension to keep projections d^3 and g^4 out of engagement, while the weight of the curtain causes it to descend. As the curtain descends the cord c is permitted to slip between the fingers and is wound upon spool c' .
- 20 20. The guide-piece b serves to keep the curtain in place against the casing and close to the window.
- 25 25. Modifications may be made in the details of construction without departing from the spirit of the invention.

Having now fully described our said invention and the manner of making and using the same, what we claim is—

- 30 30. 1. A swinging disk, D , provided with a pro-

jection on its inner face, and having a slotted arm, through which passes the curtain-cord, in combination with a second disk secured to the end of the curtain-roller, and provided with a spool, c' , a series of lugs or projections, g^4 , and a collar, g^2 , substantially as and for the purpose described.

2. The combination of a swinging disk having a projection, d^3 , a hanging piece or bearing, e , supported by said disk, a second disk secured to the curtain-roller, and provided also with a collar which passes through a slot in said swinging disk, and a cord passing through a slotted arm in said swinging disk, substantially as described.

3. In a curtain-fixture, the combination of the main cord for supporting the same, a swinging disk to which one end of said cord is attached, a hanging piece or bearing supported by said swinging disk, devices, as specified, for rolling and unrolling the curtain and holding the same in position, and a double knob for securing said main cord, substantially as described.

4. The combination of swinging disk D , main cord B , attached thereto, disk G , provided with fastening devices, as specified, guide-piece b , to which the other end of said cord is attached, link b' , cord E , and knob F , substantially as described.

JOSEPH DARLING.
